(57) **CLAIM**

The ornamental design for a tire tread, as shown and described.

DESCRIPTION

FIG. 1 is a perspective view of a tire tread, it being understood that the tread pattern repeats uniformly throughout the circumference of the tire.

FIG. 2 is a front elevation view thereof.

FIG. 3 is a left side elevation view thereof; and,

FIG. 4 is an enlarged fragmentary front view thereof.

In the drawings, the broken lines show the sidewall of the tire and form no part of the claimed design.
